UNITED STATES PATENT OFFICE.

EDWARD A. KOHN, OF NEW YORK, N. Y.

DESIGN FOR A BOTTLE.

No. 38,385.

Specification for Design.

Patented Dec. 25, 1906.

Application filed November 14, 1906. Serial No. 343,464. Term of patent 7 years.

To all whom it may concern:

Be it known that I, EDWARD A. KOHN, a citizen of the United States, and a resident of New York city, borough of Manhattan, New York, have invented a new, original, and ornamental Design for Bottles, of which the following is a specification, reference being had to the accompanying drawings, forming part thereof, wherein—

2 is a face view thereof, and Fig. 3 is a plan view showing my new design.

I claim—

The ornamental design for a bottle, as shown.

EDWARD A. KOHN.
